CLAIM

The ornamental design for an absorbent article, as shown and described.

DESCRIPTION

FIG. 1 is a perspective view showing front, bottom, and right sides of an embodiment of an absorbent article;

FIG. 2 is a view of the front side of the absorbent article of FIG. 1;

FIG. 3 is a view of the right side of the absorbent article of FIG. 1;

FIG. 4 is a view of the back side of the absorbent article of FIG. 1;

FIG. 5 is a view of the left side of the absorbent article of FIG. 1;

FIG. 6 is a view of the top side of the absorbent article of FIG. 1; and

FIG. 7 is a view of the bottom side of the absorbent article of FIG. 1.

FIG. 8 is a perspective view showing the front, bottom, and right sides of the absorbent article of FIG. 1 with alternative broken line structure;

FIG. 9 is a view of the front side of the absorbent article of FIG. 8;

FIG. 10 is a view of the right side of the absorbent article of FIG. 8;

FIG. 11 is a view of the back side of the absorbent article of FIG. 8;

FIG. 12 is a view of the left side of the absorbent article of FIG. 8;

FIG. 13 is a view of the top side of the absorbent article of FIG. 8; and,

FIG. 14 is a view of the bottom side of the absorbent article of FIG. 8.

The broken lines show portions of the absorbent article that form no part of the claimed design.

1 Claim, 8 Drawing Sheets
